UNITED STATES PATENT OFFICE.

HARRY C. BUHOUP AND GILBERT P. RITTER, OF CHICAGO, ILLINOIS.

METHOD OF MANUFACTURING CAR-WHEELS.

SPECIFICATION forming part of Letters Patent No. 717,538, dated January 6, 1903.

Application filed September 20, 1902. Serial No. 124,245. (No model.)

To all whom it may concern:

Be it known that we, HARRY C. BUHOUP and GILBERT P. RITTER, citizens of the United States, and residents of Chicago, in the county of Cook, State of Illinois, have invented certain new and useful Improvements in Methods of Manufacturing Car-Wheels; and we hereby declare the following to be a full, clear, and exact description of the same, such as will enable others skilled in the art to practice our invention.

Our invention relates to the manufacture of car-wheels, and especially to cast-steel car-wheels, and has for its object the production of cast-steel car-wheels having a condensed uniform tread.

To this end our invention, generally stated, comprises the several steps of first casting the wheel with a diameter somewhat greater than desired for the finished wheel, next corrugating the tread of the wheel or indenting the same transversely, and finally rolling or otherwise reducing the diameter of the tread of the wheel by plain rolls or in like manner, whereby a wheel having a uniformly-condensed tread is obtained.

In carrying out our invention any suitable character of devices adapted to first corrugate or indent the tread of the wheel and finally compress and plain-finish the same may be employed—as, for instance, dies, rolls, or rolling-dies; but for the purposes of this specification we have selected oppositely-disposed bed-dies.

In the drawings accompanying this specification, Figure 1 is an end elevation of apparatus adapted for practicing our invention. Fig. 2 is a vertical central section of the same. Fig. 3 is a view of the car-wheel as it passes from the corrugating or indenting devices and before it is subjected to the finishing devices, and Fig. 4 is a detached view of one of the die-plates.

Like symbols refer to like parts wherever they occur.

A indicates a suitable housing provided below with a bed B and above with a platen C, the latter adapted to travel vertically in the housing and controlled by a housing-screw or like means for exerting pressure on the platen. Journaled in the bed is a shaft b, provided with a pinion b', located within the

bed, and at its end with a gear-wheel b², and the platen C is also provided with a like shaft c, having a pinion c' and gear-wheel c², the 55 gear-wheels b² and c² meshing with an intermediate pinion d, whereby the said shafts b and c and their pinions are reversely rotated from the power-pulley D and pinion d'.

Upon the upper face of bed B and vertically above the same on the platen C are dovetail ways or guides e e and f f, in which travel reciprocating die-plates E and F, said die-plates having on their bed-faces racks with which mesh the pinions b' and c' of the 65 shafts b and c for causing the reverse travel of the die-plates E and F. The operative faces of the die-plates E and F are provided with oppositely-disposed longitudinal grooves, the cross-section of which corresponds to the 70 cross-section of the flange and tread of a car-wheel, which grooves are transversely ribbed at intervals for a portion of their length where they correspond to the tread of the car-wheel, as from x to x', and shallow gradually for a 75 certain portion of the remainder of the distance, as from x' to y', while that portion of the groove which corresponds to the flange of the wheel may also gradually shallow and narrow between x' and y' from the size of 80 the flange of the casting to that of the finished wheel in order to force any surplus metal from the flange into the tread of the wheel. The length and relative proportion of the corrugated and the plane portions of the groove 85 of the die-plate will be determined by the diameter of the wheel and the extent to which it is desired to carry the respective steps of the method. The length of the respective die-plates will preferably be multiples of the 90 circumference of the wheel.

Centered with relation to the housing and the die-plates and supported on the housings or in other suitable manner are posts G, provided with guide slots or ways g to receive 95 the ends of a mandrel H, which serves as the axis of rotation for the wheel under treatment.

H indicates a mandrel for the hub of the car-wheel blank, and h h clamps for confining the blank, the shaft H being slotted at h' and provided with wedge keys I or equivalent means for confining the car-wheel blank between the clamps and to the mandrel. The 100

mandrel H, as before noted, serves as the axis of rotation of the blank when acted on by the dies. If it is preferred to journal the ends of the mandrel in fixed boxes or pillow-blocks in lieu of allowing them vertical movement in the slots of the posts G, the bed B, as well as the platen C, will have to be constructed to travel vertically and the bed as well as the platen be provided with housing-screws in manner commonly practiced in rolling-mills.

The above-noted or other suitable devices for the purpose having been provided, a cast-steel car-wheel blank at substantially a rolling heat is secured on the mandrel H between the clamps h h, and the mandrel H inserted in the slots g of post G, so that the periphery of the blank is in vertical alinement with the grooves of the die-plates, said die-plates being drawn out to the extreme of their outward travel, so that the leading ends of the ribbed portions approach the vertical diameter of the wheel-blank. The housing screw or screws are then manipulated to cause the required rolling pressure of the dies on the periphery of the car-wheel blank, and the machine being set in operation to cause the travel of the dies the tread of the wheel will first be corrugated or indented transversely, and at the same time, if desired, the flange may be reduced, so as to turn any surplus metal into the tread of the wheel, when immediately following the transverse indentation or corrugation of the wheel-tread the said tread will be sub-

jected to the plain faces of the dies, which will condense and finish the tread, reducing its diameter to that of the finished wheel. It will be noted that the corrugations in the periphery of the blank or tread of the wheel induce the condensation of the metal of the tread on substantially radial lines by the final plain rolling and finishing, as well as limit the lateral or peripheral spread or drawing of the metal, and this is equally true no matter how the corrugations are produced, whether by casting, rolling, die-rolling, or forging; but corrugating by rolling or die-rolling is deemed preferable, as productive of a more uniform condensation in the tread of the finished wheel or blank.

Having thus described our invention, what we claim, and desire to secure by Letters Patent, is—

The method herein described for manufacturing car-wheels, which consists in first corrugating the tread of the wheel-blank and finally condensing and finishing said tread, substantially as and for the purposes specified.

In testimony whereof we affix our signatures, in presence of two witnesses, this 13th day of September, 1902.

HARRY C. BUHOUP.
GILBERT P. RITTER.
